SYSTEM FOR TRANSMITTING ELECTRICAL SIGNALS

James L. Getaz, Maryville, Tenn.

Application October 12, 1936, Serial No. 105,229
Renewed December 27, 1938

20 Claims. (Cl. 179—171.5)

This invention relates to the transmission of electrical signals and particularly to the control of the volume of the signals being transmitted.

The purposes of this invention are as follows:

- 5 1. To automatically contract the range of amplitude of the signal waves, so that this amplitude may be made as nearly constant as desired for all volumes of the sound, which is being transmitted.
- 10 2. To maintain automatically full modulation of a carrier wave of constant amplitude for all variations of volume of the signals.
- 15 3. To maintain automatically full modulation of a carrier wave at any amplitude of the carrier wave and for all variations of volume of the signals.
- 20 4. To provide means which will require a minimum of power at the transmitting station for the transmission of the desired signals.

The accompanying drawing shows a diagram of the transmission circuits and contains some features which are similar to those shown in Fig. 1 of my co-pending application Serial Number 78,808, filed May 9, 1936. In this method of transmission the circuit of the microphone contains two transformers, one of these is connected to a circuit which generates waves having a frequency below the audible frequency and proportional to the volume of sound received. These waves are fed back into the microphone and they, together with the audible sound waves, are transmitted through the other transformer to be amplified and used for modulation of a carrier wave. A particular feature of this invention is the control of the amplification of the modulating current. This is shown in three stages of amplification, and means are shown for regulating this amplification according to a fixed voltage, which is related to the amplitude of the carrier wave. A receiving circuit for this method of transmission may be similar to that shown in Fig. 2 of the above mentioned application. The drawing shows means for generating control circuits in the transmitting station which represent by their frequency the volume of sound received in the microphone. The currents produced in the microphone circuit, after being amplified, are rectified in the diode 10 and used to vary the frequency of the oscillator 19. These frequencies are combined with the frequency of an oscillator 30 and the beats thus produced are used to generate sounds below the range of audibility in the loud speaker 108, which are fed back into the microphone. The modulating current from the microphone circuit is connected to the transformer 120 and is amplified in the circuits of the tubes 122, 137 and 152. This

amplification is controlled to produce currents of a substantially constant amplitude which are proportional to the amplitude of the carrier.

In present methods of radio transmission the carrier wave is only partially modulated during most of the time it is being used for transmission. This partial modulation is necessary in transmitting ordinary signals in order to provide means for transmitting signals of larger amplitude. This partial modulation represents a waste of power which it is desired to save. In present practice it is customary to reduce the volume of the loudest signals, so that a carrier wave of sufficient power to transmit these signals at their original volume will not be required. It is also customary to amplify the weak signals so that their amplification is greater than the amplification of those signals which are stronger. But notwithstanding these contractions of the range of volume at the transmitting station, according to methods now in use, a large portion of the carrier wave is only partially modulated. The result is that much of the power used in generating the carrier wave is not utilized when weak signals are being transmitted. It is the purpose of this invention to save this power and still maintain a constant strength of the carrier wave, unless it is desirable to change the strength of the carrier wave on account of changing conditions which would affect transmission. Also a great deal of power is now used in amplifying the stronger signals. It is my purpose in this invention to save power also in amplifying the stronger signals and to spend no more power on the amplification to the strongest signals than is spent in amplifying those signals which are weakest.

To accomplish these purposes I have shown means by which all signals from the strongest to the weakest are amplified to one strength which is only strong enough to transmit the weak signals without interference from noises, and atmospheric conditions. The amplitude of the carrier wave may be limited to an amount necessary to carry this amplitude of modulation. At the receiving set these signals are restored to their original variations in amplitude in the method as shown in my former application. Should it become desirable to use a stronger or a weaker carrier wave due to changes in daylight or changes in the atmosphere, the strength of the carrier wave may be changed correspondingly and the amount of modulation will be automatically changed to correspond with the change in the strength to the carrier wave so that the carrier wave will be fully modulated at whatever

strength it is transmitted. The principles shown in this invention for the control of the volume of signals are not limited to the transmission by signals by radio, but may be used with other means of transmission.

In the accompanying drawing, the microphone circuit contains the microphone 1 which receives the sound to be transmitted, a battery 2, and the primary coils of the transformers 3 and 120. The transformer 120 is connected to circuits which modulate the carrier wave, and the transformer 3 is connected to circuits which develop currents the frequencies of which are proportional to the volume of the sound received in microphone 1.

The current from the secondary of transformer 3 passes through the high pass filter 100 which filters out any frequencies below the audible range. The current from this filter 100 is amplified in the circuit containing the triode 102, batteries 101 and 103 and transformer 104. It is then rectified in the circuit containing diode 10, resistance 8 and condenser 9. The rectification of this current of audible frequency produces an envelope in which the amplitude represents the variations in signal strength. The ends of this resistance 8 are connected to the grid and filament of the triode 12. The circuit of this triode 12 amplifies the voltage variations in the envelope produced by the diode 10, and this circuit contains the battery 11, the battery 14, the choke coil 13, and the saturation reactor 15. This saturation reactor is connected in the circuit of the oscillating tube 19, which consists of the feed back coil 17, the condenser 18, the battery 22 and the resistance 21 which is by-passed by the condenser 20. This oscillating circuit is adjusted to produce oscillations of medium frequency, the frequency of these oscillations are varied by the saturation reactor 15, and are transmitted to the grid of the triode 33 by connections to the transformer 23.

Another oscillating circuit consists of the triode 30, the feed back coil 25, the condenser 27, the battery 31 and the resistance 29, which is by-passed by the condenser 28. The circuit is adjusted to produce oscillations of about the same frequency as those produced by the tube 19 and is connected to the grid of the triode 33 by the transformer 24. This circuit maintains a constant frequency.

The frequency of the beats between these two oscillating circuits varies as the frequency of the oscillations, produced by tube 19, is varied by the saturation reactor 15. By proper adjustment of the two oscillating circuits the frequency of these beats may be made to vary inversely with the amplitude of the direct current envelope and they may be confined to a narrow band below the audible frequency. The oscillations of these two circuits are rectified by triode 33 in the circuit consisting of the battery 32, the battery 46 and the condenser 34, and the beats are transmitted through the transformer 35 and the low pass filter 36, which filters out any harmonics. These low frequency beats are connected to the loud speaker 108, and thereby produce sounds below the audible range which are received by the microphone 1. The microphone circuit then contains in addition to the signals which are to be transmitted low frequency signals which vary in frequency in proportion to the average volume of the signals being transmitted. These low frequency signals in the microphone circuit which are produced by the sub-audible beats, are volume control signals. They represent by their frequency the volume of the sound transmitted. In

the receiving set they function in a similar manner to the volume control signals shown in my co-pending application 78,808, mentioned above. In that application the low frequency volume signals are used to modulate the carrier. In this application these low frequency volume signals are also transmitted on the carrier to serve as volume control signals in the receiving set. Instead of being applied directly to modulate the carrier, they are used to produce sub-audible sound waves in the speaker 108. These low frequency sound waves produce low frequency signals in the microphone circuit, which represent by their frequency the volume of sound being transmitted. These low frequency signals in the microphone circuit, together with the sound signals in that circuit, are used to modulate the carrier.

As shown below, before these signals are used for modulation, the amplitude of the sound signals is regulated by reducing the amplification of the loud signals, and increasing the amplification of the weak signals until the amplitude of all of the sound signals is substantially the same. Thus the carrier is modulated with two kinds of signals by the same modulating current. One kind of signal is of substantially constant amplitude and represents by its frequency the frequency of the sound being transmitted, and the other signals are of substantially constant amplitude and represent by their frequency the volume of the sound being transmitted.

These signals are transmitted to the transformer 120 through the connections 43 and 44 and thence through the connections 155 and 156 to the transmitter modulator, which is not shown. The purpose of the intervening circuits is to regulate the volume of the signals for the purposes mentioned above. In order to hold this amplitude to a constant value and to fully modulate the carrier at all times, it is desirable to amplify these signals by comparison with a constant voltage, or a voltage which is in constant ratio with the amplitude of the carrier wave, and this is accomplished as follows.

The transformer 120 is connected to the grid and filament of the triode 122. This circuit of triode 122 contains the battery 123, condenser 121 and transformers 124 and 125. The current from the transformer 125 is rectified in the circuit containing the diode 128, resistance 126 and condenser 127.

The carrier current is generated by the alternator 133 and across the connections 157 and 158 of this circuit are the resistances 132 and 149. The wires 157 and 158 lead to the transmitter modulator. Connected to the ends of the resistance 132 is the circuit of the diode 131 containing the resistance 129 and condenser 130. The positive ends of resistances 126 and 129 are connected together. The negative end of resistance 129 is connected to the filament of the triode 122 and the negative end of resistance 126 is connected to its grid. If the drop in voltage across the resistance 132 is greater than the voltage produced in the secondary of transformer 125, the filament of 122 will be made more negative and the grid more positive and the amplification is increased. Conversely if the drop in voltage across 132 is less than produced in transformer 125, the grid of 122 will be made more negative and the amplification reduced. The drop in voltage across the resistance 132 is constant with constant strength of carrier current, and by this standard of comparison the

amplitude of the signal current may be amplified so as to be more nearly constant. If the strength of the carrier current is changed, the standard of comparison for the strength of the signal current is changed correspondingly.

This process may be repeated by the circuits of the triode 137 and the diodes 143 and 148. The circuit of the diode 148 is connected across the resistance 149 with the adjustable connection 150 and this circuit contains the resistance 146 and the condenser 147. The circuit of the diode 143 contains the resistance 142 and the condenser 141 and is connected to the transformer 139 in the circuit of the triode 137.

15 The negative end of resistance 148 is connected by the wire 144 to the filament of triode 137 and the negative end of resistance 142 is connected by the wire 145 to the grid of triode 137. These last mentioned circuits are used to correct any variations of amplitude which may not be made uniform by their amplification in the circuit of triode 122, and the adjustment of connection 150 to the resistance 149 is used to adjust the amplification to obtain full modulation. 20 The control of the amplification in the circuits of triodes 122 and 137 may be obtained in a variety of ways. The resistances 129 and 146 may be connected to any other source of constant voltage and be independent of the connection to the current which produces the carrier wave. The condensers 127 and 141 may be made of such capacities as to regulate the speed with which the change in rate of amplification follows a change in input voltage in the triodes 30 122 and 137. The condenser 127 and resistor 126 may be set so that the circuit of diode 128 will respond with greatest speed. With the result that if a peak of amplitude is impressed on the grid of triode 122 the connection to the negative end of resistance 126 will make the grid less positive and reduce the amplification. The constant voltage supplied to the resistance 129 may be adjusted so that the changes in amplification take out the peaks of amplitude of 35 the signal currents.

40 With the peaks of the current removed and the weaker signals amplified more in proportion than the average signals, the current is impressed on the triode 137. The condenser 141 may be of such capacity that the voltage applied to the grid and filament of triode 137 will respond more slowly to the changes in the input voltage. With the result that the changes in the rate of amplification in the triode 137 will follow inversely the average changes in amplitude. Another method of adjusting these circuits for controlling amplification is to fix resistors 126 and 142 and the capacities of the condensers 127 and 141 for the greatest frequency of response in 45 changing the rate of amplification. By this means the syllabic variations in amplitude may be made uniform and speech converts into an unintelligible mumble. The original amplitude may be restored by setting the control of amplitude in the receiver for a corresponding frequency of response. Such a receiver is shown in my application Serial No. 78,808 mentioned above. There will still be some slight variations in amplitude producing the voltages in the circuit of 144 and 145 and these may be corrected by connecting these wires to the filament and grid of triode 154. In this circuit consisting of triode 152, battery 153, condenser 151 and transformer 154 the signals are further amplified and pass from thence through wires 155 and 156 to

the transmitter modulator as mentioned above.

This method of transmission may be summarized as follows. The signals from the microphone are amplified and rectified and passed through a saturation reactor to an oscillating circuit of medium frequency as mentioned in my co-pending application. The variations in frequency produced in this oscillating circuit and combined with another oscillating circuit producing beats of very low frequency which are 10 transmitted to the microphone through the loud speaker 108. The microphone circuit then contains the original signals and low frequency signals below the audible range which vary in frequency according to the variation in volume of 15 the signals to be transmitted.

The low frequency signals are eliminated from the triode 102 by the high pass filter 100, but are included in the connections to the transmitter modulator. The circuit to the transmitter modulator is amplified by comparison with a constant voltage which is obtained across the connection of the alternator producing the carrier wave. By amplifying the signals in comparison with a constant voltage and varying the amount of amplification so as to make the voltage corresponding to the strength of the signals equal to the constant voltage, a constant amplitude of signals is obtained.

25 By reducing the signals to a constant amplitude, the carrier may always be fully modulated and the power for modulation and the power for generating the carrier wave may be limited to the power necessary to transmit signals free from interference by noises or atmospheric conditions.

30 At the receiving station the signals are restored to their original variations in amplitude by comparison with the variations in frequency of the volume signals.

35 This invention is shown and described as referring to the transmission of electrical signals which represent sound signals. It is apparent that it may be applied to electrical signals which represent other forms of intelligence signals besides sound, and it is intended to include the 40 control of electrical signals which are used to transmit intelligence signals in any form.

45 I claim:

1. In a system for transmitting signals, an electrical transmitter circuit, means for generating 50 waves of electrical energy in said circuit corresponding to the signals being transmitted, means for generating control currents which vary in frequency with the volume of said signal, means for producing inaudible sound waves corresponding 55 in frequency to said control currents and means for generating waves of electrical energy in said transmitter circuit corresponding to said inaudible sound waves.

2. In a system for transmitting electrical signals, means for carrying said signals, means for obtaining a predetermined reference voltage, means for rectifying said signals and producing a direct current voltage from said signals, the envelope of which varies in voltage with the amplitude of said signals, means for amplifying said signals, and means for increasing and decreasing the rate of said amplification by comparing said variable voltage with said reference voltage.

3. In a system for transmitting electrical signals by radio, means for generating a carrier wave which is modulated by said signals, means for rectifying said signals and producing a direct current voltage from said signals, the envelope of which varies in voltage with the amplitude of 70 75

5 said signals, means for amplifying said signals, means for rectifying said carrier wave and producing a direct current envelope which corresponds in voltage with the amplitude of said carrier wave, means for using these two voltages to regulate the amplification of said signals.

10 6. In a system for transmitting electrical signals, a transmitting means of minimum capacity, a means for obtaining a reference voltage which is proportional to the capacity of said transmitting means, means for producing a direct current voltage from said signals the envelope of which varies in voltage with the amplitude of said signals, means for amplifying said signals, and means for increasing the amount of said 15 amplification if said variable voltage is less than said constant voltage.

20 7. In a system for transmitting electrical signals, a transmitting means of minimum capacity, a means for obtaining a reference voltage which is proportional to the capacity of said transmitting means, means for producing a direct current voltage from said signals the envelope of which varies in voltage with the amplitude of said signals, means for amplifying said signals, and means for reducing the amount of said 25 amplification if said variable voltage is greater than said reference voltage.

30 8. In a system for transmitting electrical signals by radio, means for generating a carrier wave, means for obtaining a voltage which is proportional to the amplitude of said carrier wave, means for automatically varying the amplitude of said signals so that all of said signals have substantially the same amplitude and means for automatically regulating the amplitude of said signals so that said amplitude has a fixed relation to said voltage.

35 9. The steps in a method of communicating signal energy of variable intensity which comprise generating a flow of electrical energy which varies in amplitude and frequency corresponding to the varying characteristics of said signals in combination with a flow of electrical energy which varies in frequency corresponding to the 40 variation in volume of said signals, generating a carrier wave, developing a voltage which is proportional to the intensity of said carrier wave, amplifying this combined flow of electrical energy to a substantially constant amplitude which 45 has a substantially fixed relation to said voltage and producing a modulation of substantially constant amplitude in said carrier wave with said combined flow of electrical energy.

50 10. The steps in a method of communicating signal energy of variable intensity which comprise generating a flow of energy which varies in amplitude and frequency corresponding to the varying characteristics of said signals in combination with a flow of electrical energy which varies in frequency corresponding to the variation in volume of said signals, generating a carrier wave, developing a voltage which is proportional to the intensity of said carrier wave, automatically amplifying said combined flow of electrical energy with a varying degree of amplification which is inversely proportional to the varying intensity of said flow of energy until the intensity of said combined flow of electrical energy 55 is more nearly constant and which is substantially equal to said proportional intensity and modulating said carrier wave with said combined flow of energy of modified intensity.

75 11. The steps in a method of communicating signal energy of variable intensity which com-

prise generating a flow of energy which varies in amplitude and frequency corresponding to the varying characteristics of said signals in combination with a flow of energy which varies in frequency corresponding to the variation in volume of said signals generating a carrier wave, developing an intensity which is proportional to the intensity of said carrier wave, automatically amplifying said combined flow of energy with a varying degree of amplification which produces 10 in said flow of energy a transformation of its intensity, said intensity being more nearly constant for a given intensity of a carrier wave and being substantially equal to said proportional intensity, and modulating this carrier wave with 15 said combined flow of energy at its changed intensity.

10. The steps in a method of communicating signal energy of variable intensity which comprise, generating a similar energy of substantially 20 constant intensity which is proportional to the intensity of a carrier medium, amplifying the intensity of said signal energy, automatically raising said rate of amplification to bring the intensity of said signals up to said constant intensity if the intensity of said signal energy is less than said constant intensity and decreasing said amplification if the intensity of said signal energy is greater than said constant intensity, and modulating said carrier medium with said 25 signal energy of modified intensity.

11. The steps in a method of communicating signal energy of variable intensity, which comprise, generating a substantially constant carrier wave, and obtaining a voltage from said carrier wave which is proportional in intensity to the intensity of said carrier wave, amplifying said signal energy of variable intensity, and automatically increasing the amplification of said variable intensity when it is less than said voltage which 40 is proportional to said carrier wave.

12. In a system for transmitting electrical signals, a transmitting means for said signals of minimum capacity, means for amplifying said signals, means for rectifying said signals, means for producing a voltage which represents the variations in amplitude of said signals, means for obtaining a source of substantially constant voltage which has a definite relation to the capacity of said transmitting means, means for comparing the voltage produced by said signals with said constant voltage and means for contracting the variation in amplitude of said signals by raising the rate of said amplification to bring said representative voltage up to said constant voltage and decreasing said rate of amplification, according as to whether the voltage representing said signals is less or greater than said constant voltage.

13. In a system for transmitting electrical signals, a transmitting means of minimum capacity, means for producing a direct current voltage from said signals, the envelope of which varies in voltage with the amplitude of said signals, means for obtaining a substantially constant voltage which has a definite relation to the capacity of said transmitting means, means for amplifying said signals and means for automatically raising the rate of said amplification to increase the voltage representing weak signals if said variable voltage produced by said weak signals is less 70 than said constant voltage.

14. A method of transmitting intelligence signals of variable intensity, which comprises, generating a carrier wave of substantially constant frequency, obtaining an intensity of voltage pro-

portional to the intensity of said carrier, generating control signals which represent by their frequency the intensity of said intelligence signals, amplifying said intelligence signals, varying the rate of said amplification so that all signals of variable intensity are amplified to substantially equal said proportional intensity which is proportional to the intensity of said carrier wave, modulating said carrier wave with currents which contain said intelligence signals of substantially constant intensity and said control signals.

15. A method of transmitting signals of variable frequency and variable intensity, which comprises, generating a carrier wave, obtaining a voltage proportional to the amplitude of said carrier, generating waves of electrical energy flow containing frequencies which vary according to the variable frequencies of said signals, and containing frequencies which represent by their variation the variable intensity of said signals, amplifying said flow of electrical energy, varying the rate of said amplification to produce an amplitude which has a fixed relation to said proportional voltage in said flow of electrical energy, modulating said carrier wave according to the characteristics of said energy flow.

16. In a system for transmitting electrical signals by radio, means for generating a carrier wave, means for obtaining a voltage which represents a definite proportion of the amplitude of said carrier wave, means for amplifying said signals, means for rectifying said signals and obtaining a voltage which represents the amplitude of said signals, means for comparing said voltages, means for automatically regulating the amplification of said signals to approximately equal said proportion of the amplitude of said carrier wave by the difference between said voltages.

17. The steps in a method of communicating signal energy of variable intensity, which comprise, generating a flow of electrical energy which contains variations in amplitude corresponding to the varying characteristics of said signals, and which contains variations in frequency corresponding to the variations in the volume of said signals, generating a carrier frequency wave, ob-

taining a voltage proportional to the amplitude of said carrier wave, amplifying said flow of electrical energy to a definite relation to said proportional voltage, and modulating said carrier wave with said combined flow of electrical energy. 5

18. In a system for transmitting electrical signals by radio, means for generating a carrier frequency wave, means for generating a constant voltage, which is proportional to the amplitude of said carrier wave, means for amplifying said signals, means for obtaining a voltage which is proportional to the amplitude of said signals, means for obtaining the differential of said voltages, means for varying the amplification of said signals so that all of said signals have substantially the same amplitude, and means for regulating said amplitude of said signals by the differential of said voltages. 10 15

19. A method of transmitting signals of variable frequency and variable intensity, which comprises, generating a carrier wave, obtaining an intensity of voltage proportional to the intensity of said carrier wave, generating alternating currents which have an intensity substantially equal to said proportional intensity, and which represent by their frequency said variable frequency of said signals, generating alternating currents which represent by their frequency the variable intensity of said signals, modulating said carrier wave with said alternating currents. 20 25 30

20. A method of transmitting signals of variable frequency and variable intensity, which comprises, generating a carrier wave, obtaining an intensity of voltage proportional to the intensity of said carrier wave, producing waves of electrical energy flow substantially equal to said proportional intensity which are equivalent in frequency to the variable frequency of said signals, producing waves of electrical energy flow of substantially constant intensity which have a 40 variation in frequency representative of the variations in intensity of said signals, modulating said carrier wave in accordance with the variations in frequencies of said flows of electrical energy. 45
